JOHN F. PETERSON AND THOMAS S. KIRBY, OF MADISON, ALABAMA.

HARVESTER'S BAG.

1,192,344.

Specification of Letters Patent. Patented July 25, 1916.

Application filed January 22, 1916. Serial No. 73,651.

To all whom it may concern:

Be it known that we, JOHN F. PETERSON and THOMAS S. KIRBY, citizens of the United States, residing at Madison, in the county 5 of Madison and State of Alabama, have invented a new and useful Harvester's Bag, of which the following is a specification.

The present invention relates to an improved harvester's bag, and has for an object 10 to provide a bag of this character with a collapsible mouth, which when folded, admits the rolling or folding of the bag into compact size; to provide a bag with a supporting apron and supporting strips which 15 are used not only to support the bag upon the person, but which also serve the purpose of closing and securing the bag for carrying, weighing, and transportation by rail, or the like; and to provide a bag and supporting 20 means therefor, which when attached to the person gathering the cotton, fruit, vegetables, or the like, hangs against the back of the person, counterbalances the body of the person when stooping, and when walking, 25 and prevents the tiring and straining of the back.

Another object of this invention is to provide a bag, and an apron therefor, formed in one piece or length of material; to provide 30 a bag with a collapsible ring or hook in the mouth thereof, and provide the ring with a stop joint to hold the bag open when the ring is extended, so that the mouth of the bag will be held in position to readily 35 receive the cotton, fruit, vegetables, or the like, being picked, or gathered; and to provide a harvester's bag which may be so attached to the person that both hands are free to pick or gather, and thus permit 40 the gathering in of a greater amount in a given time than with the bags and baskets now employed, and which must be constantly stealed by hand.

Various other objects and advantages of 45 this invention will be clearly brought out from the following specific disclosure of the present preferred embodiment, shown in the accompanying drawing, wherein—

Figure 1 is a front elevation of the bag 50 in position on the person, the mouth of the bag being open to receive its contents from time to time as picked or gathered. Fig. 2 is a vertical central section, taken through

the bag in open position. Fig. 3 is a front elevation of the bag when filled and closed, 55 showing the shoulder straps thereof extending downwardly against the front of the bag to hold the apron over the top thereof. Fig. 4 is a similar view, showing a slightly different arrangement of the shoulder straps, 60 which in this instance encircle the bag. Fig. 5 is a detail perspective view of the ring secured in the mouth of the bag, this figure showing the ring extended or open.

Referring to this drawing, wherein like 65 parts are designated by similar characters of reference, 10 designates a bag made of any suitable strong flexible material, and which is provided upon its inner side with an upwardly extending apron 11. As may be best 70 seen from Fig. 2, the apron 11 and the body of the bag 10 are formed of one continuous piece or length of material, which extends from the top of the apron 11 down to the bottom of the bag, and is thence returned 75 upwardly and stitched along its meeting edges, as at 12, to provide the inclosure at the bottom or loop of the strip, and the upwardly extending apron 11 at the top of the strip. It will be noted that the free ends of 80 the strip are overturned and stitched to provide a hem 13 along the upper and lateral edges of the apron 11, and a hem 14 around the upper marginal edge of the mouth of the bag and at the front thereof. The mouth 85 of the bag 10 is provided with a band or strip 15, which extends entirely around the mouth of the bag and against the inner wall thereof, and which is stitched at its upper and lower edges to provide, between the 90 band 15 and the front and rear walls of the bag, an annular passage or channel 16 in which is placed a folding ring or loop 17. As shown to advantage in Fig. 5, this ring 95 17 is made in two sections, which are semi-circular in form and made preferably of heavy wire. The section 17 of the ring is provided with loop eyes 18, which extend in a vertical plane from the ends of the section 17 and are offset downwardly to provide a support or rest 19 at each end of the section 17. The opposite semi-circular section 17¹ is provided at its opposite ends with horizontal loops 20 forming eyes for pivotal engagement through the vertical eyes 18, so 100 as to hingedly connect the opposite sections 105

of the ring, and admit the sections to be swung over in either direction, one upon the other. The horizontal loops or eyes 20 terminate in extensions or fingers 21, which are curved outwardly from the ends of the loops 20, are carried longitudinally beyond the vertical eyes 18, and are thence bent inwardly into the path of the supporting shoulders 19 to engage the same and hold the section 17 from swinging downwardly out of the horizontal plane of the opposite section 17¹. Thus, the ring 17 may be collapsed by swinging either section upwardly and over onto the opposite section, but the ring is held extended by the fingers 21 and the shoulders 19, so that the sections of the ring cannot fall and must necessarily hold the mouth of the bag open when adjusted in the position shown in Fig. 2.

20 The bag 10 is adapted to hang against the back of the person, who is picking or gathering, and to be located, by the adjustment of the shoulder straps 22, below the waist or seat of the person, and also to be suspended from the shoulders of the person, so as to counter-balance the weight of the body of the person when stooping over, or when walking in upright position. The apron 11 is adapted to rest against the back 30 of the person and conform to the curvature thereof, as is shown to advantage in Figs. 1 and 2. The upper edge 13 of the apron carries a pair of spaced apart shoulder straps 22 adjustable as to length by means 35 of buckles 23, and provided upon their upper ends with snap hooks 24. The straps 22 are adapted to pass upwardly over the shoulders, be crossed in front, and carried downwardly and backwardly beneath the 40 arms where the snap hooks 24 are adapted to engage with rings 25 secured preferably to the upper free corners of the apron 11. In this manner, the straps 22 hold the apron 11 up upon the back, and the free ends of 45 the straps engaging the free corners of the apron, bend and hold the apron across the back, so that the apron fits snugly thereagainst, and conforms to the curvature thereof. Thus, the apron is firmly held 50 across the back of the picker, the bag hangs down close against the back, and the body of the bag lies wholly below the waist or seat of the person carrying the bag. As the weight of the bag and its contents are thus 55 disposed below the waist line, a slight forward inclination of the body counter-balances the weight of the bag, so that practically no strain is placed upon the back and the bag assists in supporting the body when 60 the picker is stooping to gather or pick the contents of the bag. The ring 17 holds the mouth of the bag open so that the picker may easily reach around from either side and deposit the cotton, or the like, in the

bag, without the necessity of drawing the 65 bag around to the side and opening it, or otherwise adjusting the bag.

After the bag has been filled, the snap hooks 24 are released from the rings 25 and the bag is permitted to drop to the ground 70 from the back of the picker. The apron 11 is now carried forwardly over the mouth of the bag, which mouth is collapsed as far as is possible by the swinging upwardly of the outer section of the ring 17, and the free 75 edge 13 of the apron is drawn down against the front of the bag. The shoulder straps 22 are now utilized for securing the apron 11 over the mouth of the bag, and to accomplish this purpose, the straps 22 are preferably crossed and passed through the opposite corner rings 25 of the apron, so as to draw the corners of the apron taut down against the front of the bag and completely close the top thereof. As shown in Fig. 3, 80 85 the straps 22 may be carried directly downward and the snap hooks 24 secured to a bottom central securing ring 26, which is secured to the lower end of the bag intermediate its lateral edges by means of a 90 tab 27.

As shown in Fig. 4 of the drawing, the supporting straps, after passing through the corner rings 25 of the apron, may be wound oppositely around the body 10 of the bag 95 and finally brought together at the bottom adjacent the ring 26, so that the snap hooks 24 may be engaged in the ring 26 to securely hold the straps 22^a about the bag. In each instance, however, it is desired to 100 weigh the bag, and it will be readily understood that the hook of the scale may be passed beneath the straps 22 of Fig. 3 midway between the top and bottom of the bag, or the scale hook may be engaged beneath 105 the crossed portions of the straps 22^a, as shown in Fig. 4 in dotted lines, so as to counter-balance the opposite ends of the bag upon the scale hook.

In suspending the bag relatively low on 110 the back of the harvester, the products picked or gathered may be more easily dropped in the open top of the bag by swinging the arms backwardly without appreciably raising the same. Thus easy access to the bag is had by this low position 115 thereof.

It is, of course, understood that it is within the spirit of this invention to make such changes or modifications as will be found 120 necessary in the manufacture and use of this device, such variations being limited only by the scope of the following claims.

What is claimed is:—

1. A harvester's bag comprising a bag 125 with an upwardly opening mouth, an apron extending upwardly from and forming a continuation of one side of said mouth, a

device arranged within the mouth of the bag to maintain it in an open position, said device being collapsible to close said mouth, said apron being adapted for engagement 5 across the back of a person and to be folded down over the mouth of the bag when closed to hold the mouth in closed position, a pair of shoulder straps secured to the apron and extending upwardly therefrom, securing 10 means for engagement with the free ends of the straps to hold the straps looped over the shoulders and support the apron and the bag, and a second securing means at the bottom of the bag to hold the straps taut when 15 the apron is in its folded position.

2. A harvester's bag comprising a bag having an upwardly opening mouth, an apron extending upwardly from and forming a continuation of one side of said mouth, 20 a pair of shoulder straps carried by the apron and adapted for engagement over the shoulders of a person to support the bag, and a pair of rings carried at the upper portion of the apron and adapted to receive the 25 shoulder straps to hold the apron in extended position, said apron when the bag is filled being adapted to be folded forwardly over the mouth of the bag with said straps passed through said rings to hold the apron 30 in closed position.

3. A harvester's bag comprising a body portion having an open upper end, an apron adapted to fit across the back of the person and extending upwardly to support the bag 35 below the waist or seat, a pair of shoulder straps carried by the apron and adapted for engagement over the shoulders of the person to support the bag, a pair of rings carried upon the upper corners of the apron 40 and adapted to receive the ends of the shoulder straps to hold the same in position, said apron when the bag is filled being adapted to be folded forwardly over the open end of the bag and said straps being adapted to be 45 crossed and passed through said rings to draw the corners of the apron tightly over the top of the bag, and means for securing said straps in taut position against the bag.

4. A harvester's bag comprising a bag 50 and an upwardly extending apron at one side of the bag, a two-part ring secured in the mouth of the bag and having interlocking looped eyes at the meeting ends of the parts, the looped eyes of one of the parts 55 having stop fingers projecting into the path of the opposite part to hold the parts in extended position when the bag is open, supporting straps carried by the apron for engagement over the shoulders of the har- 60 vester, means for holding the supporting straps in position, the parts of said ring being adapted to be folded to close the upper end of the bag, said apron being adapted to be drawn over the top of the bag and down

against the opposite side thereof and means 65 for holding said shoulder straps taut against the side of the bag to bind the apron over the top of the bag.

5. A harvester's bag comprising a bag with an upwardly opening mouth, an apron 70 extending upwardly from and forming a continuation of one side of said mouth, a device arranged within the mouth of the bag to maintain it in an open position, said de- 75 vice being collapsible to close said mouth, said apron being adapted for engagement across the back of a person and to be folded down over the mouth of the bag when closed to hold the mouth in closed position, and means connected with the apron for sus- 80 pending the bag from the shoulders of the person with the apron over the back of the latter, said suspending means constituting means for holding the apron in its closed position over the mouth of the bag. 85

6. A harvester's bag comprising a single strip returning upon itself with one end extending beyond the other and being stitched along the overturned edges to pro- 90 vide a bag with an upwardly opening mouth and an apron extending upwardly beyond and forming a continuation of one side of the mouth, means connected to the apron for suspending the bag from the shoulders of a person, and a collapsible frame in the mouth 95 of the bag for holding the mouth open and adapted to be folded to collapse the bag and bring its opposite upper edges together, said apron being adapted for engagement across the back of the person and to be folded down 100 over the mouth of the bag when collapsed for holding the mouth closed.

7. A harvester's bag comprising an apron adapted for securement upon the back of the harvester, a bag suspended from the 105 apron, a two-part ring secured in the mouth of the bag, one part having vertical loops upon its opposite ends offset to provide a rest at each end of the part inwardly of the loops, horizontal loops provided upon the 110 ends of the opposite part and engaging through the vertical loops of the first part to hingedly connect the two parts of the ring, the horizontal loops having fingers projecting from the terminals thereof and 115 extending into the paths of said rests to engage the same when the parts are fully opened to hold the mouth of the bag ex- tended.

8. A harvester's bag comprising a bag 120 with an upwardly opening mouth, an apron extending upwardly from and forming a continuation of one side of said mouth, said apron being adapted to be folded down so as to close over the mouth of the bag, shoulder straps connected to the apron for sus- 125 pending the bag from the shoulders of a person, and a fastening device at the bot-

tom of the bag to which the said straps are connected and held in taut relation when the apron is folded over the mouth of the bag, whereby the bag is kept in closed position and the straps are adapted to be engaged by a scale in weighing the contents of the bag.

In testimony, that we claim the foregoing

as our own, we have hereto affixed our signatures in the presence of two witnesses.
